UNITED STATES PATENT OFFICE.

OSCAR OTTERSON, OF BUTLER, PENNSYLVANIA.

RAILWAY-CAR CONSTRUCTION.

1,040,572.

Specification of Letters Patent.

Patented Oct. 8, 1912.

Application filed February 28, 1912. Serial No. 680,001.

To all whom it may concern:

Be it known that I, OSCAR OTTERSON, a resident of Butler, in the county of Butler and State of Pennsylvania, have invented a new and useful Improvement in Railway-Car Construction, of which the following is a specification.

This invention relates to railway-car construction and especially to the construction of steel railway cars.

The object of the invention is to provide an improved construction and arrangement of parts for securing a panel or sheet of material in position in such manner that it may be readily attached to or detached from its frame, and in which the same is securely held in place without the aid of putty, bolts, screws, nails or other similar means.

The invention comprises the construction and arrangement of parts hereinafter described and claimed.

In the drawings Figure 1 is a cross sectional view showing my invention applied for securing an interior finish panel to the roof or side wall of a sheet metal car; Fig. 2 is a similar view showing another form of the invention; Fig. 3 is a cross sectional view showing one form of my invention applied for securing a pane of glass or other form of panel to a window sash or door frame; Fig. 4 is a detail view showing the manner of insertion of a panel and bead into place; Fig. 5 is a plan view of one end of one form of bead or retainer; and Figs. 6, 7, 8 and 9 are cross sectional views showing modified forms of the invention.

In the drawings, 1 represents the frame member to or in which the panel or sheet of material 2 is secured. This may be either a fixed portion of the body of the car, as for example, its roof or side wall, members secured thereto, or a window sash or door frame and the panel may be of metal, glass, or other material. Other uses of the invention and applications of the same will be readily apparent. In Fig. 1 the panel or sheet of material 2 is the interior finish, or ceiling or side panel of the car and is secured to the roof or wall 1, between ribs, beams or boxes 3 forming part of the frame and extending entirely around the edges of the panel. The frame member 1 comprises also a holding member 4 riveted to the box or beam 3, and preferably formed of cold drawn steel, shaped as shown and provided with a groove or channel 5 to receive a bead

or retainer 6 for holding the panel or sheet of material 2. The groove or channel 5 is formed between an offset portion 12 of the frame and an abutment or seat 8 against which the panel or sheet of material 2 is pressed or held. The bead or retainer 6 is formed of cold drawn steel and may be of various shapes and configurations. In the form shown in Fig. 1 the bead or retainer 6 is formed with a curved or arched web or body 6^a, having one edge portion turned in the form of flat leaf or flange 7 bearing against the outside surface of the panel or sheet of material 2 to press or force it against its seat or abutment 8, as stated. The bead or retainer 6 is also provided, at the other side of its web or body portion 6^a, with an indented locking portion 10 having an inturned flat face 11 seated behind the offset 12 of the frame, and a flat face 13 at right angles thereto and seated on the outer face of the offset. As shown, the offset is somewhat remote from the seat or abutment 8 in a direction 70 normal to the panel 2. Continuous with the locking portion 10 of the bead or retainer 6 is a keeper flange or spring member 14, to assist in keeping the bead in place and which is arched as shown and in the 75 assembled structure may be seated or engaged either directly under the edge of the panel 2 or, if preferred, under a rib or flange 9 of the frame and which is located over the groove or channel 5 and is normal 80 to abutment 8.

The keeper flange or spring 14 may be formed either as a continuation of the locking portion 10, as shown in Fig. 1, or as a continuation of the flat leaf or flange 7, as 95 shown in Figs. 2 and 6. The panel or sheet of material 2 may be square, rectangular or of other shapes, and in assembling is held in place with its inner surface against the seat or abutment 8 around the edges of the 100 frame, while the beads or retainers 6 are inserted into place. To accomplish this, each bead or retainer is compressed or flexed, both to bring its flat leaf or flange 7 and locking portion 10 closer together, and also 105 as an entirety from end to end. The ends of the bead or retainer are either mitered to form a close joint at the corners, or are otherwise so formed as to permit of slipping the ends thereof into place after flexing or 110 bending of the bead and then snapping it into locking position with the flange or

spring member 14 seated in the channel 5 and under or behind flange 9 and the locking portion 10 in place behind the offset 12. With either of the forms shown in Figs. 1 5 and 2 the bead is easily removed by inserting a suitable tool, as for example, a screw driver or wedge, under the flat face 13 of the locking portion 10 and prying up and out on the bead.

10 Fig. 2 illustrates another form of the invention in which the bead or retainer 6 is formed with a flat leaf or flange 7 engaged with one side of the panel 2 and the locking portion 10 seated behind the offset 12 of the 15 frame member, as in the form just described. In this form of the invention, however, the bead 6 is provided with a keeper flange 14 which is formed as a continuation of the flat leaf 7, and which engages directly with the 20 edge of the panel or sheet of material 2. In each of the forms shown in Figs. 1 and 2 the bead is under tension both before and after being seated in position and any tendency of the panel or sheet of material 2 to 25 become loosened or to lose its position results in merely increasing the tension in the bead and its resistance to displacement of the panel. In the form shown in Fig. 2 the flange 7 presses the panel 2 tightly against 30 the filling block 15 of the frame member 4, while the keeper 14 of the bead presses edgewise against the panel and, in co-operation with the companion keeper at the other edge of the sheet or panel, holds 35 the same securely in position. This result is secured by reason of the fact that any edgewise movement of the panel swings the entire bead around the offset 12 as a center and forces the flange 7 more tightly against the 40 panel.

If desired, the offsets 12 on the holding members 4 of the frame may be formed, as shown in Fig. 4, that is, of full height opposite the middle of a panel and decreasing to 45 nothing at each end. With this form of the invention the bead is flexed or bent from end to end and its ends snapped into place in the corners as before. The body of the bead, however, may then be more easily pushed to 50 its seat behind the offset to secure the bead in place.

In Fig. 3, I have shown the application of that form of my invention shown in Fig. 1, for securing either a pane of glass or a decorative or other panel in a window sash or door frame. In this view, the opposite frame members 1 are either the vertical side stiles of a window sash or the vertical side members of a door frame. This may 55 either be formed solid and of wood or metal, shaped with a groove or channel 5, as shown, to receive the bead or retainer 6 for the panel or glass in the same manner as the holding or frame member 4 in Fig. 1. If 60 the frame 1 is formed of cold drawn steel,

suitable bracing members 16 may be welded or otherwise secured at their ends between the inner and outer portions 17 of the frame to space the same apart and to give rigidity to the structure. In this form of the invention, the groove or channel 5 is formed to provide the offset 12, behind which is seated the locking portion of bead 6, and the abutment or seat 8, as before.

In this construction also, the keeper 75 flange or spring 14 is formed continuous with locking portion 10 and is arched and seated under the edge of the sheet of material or pane of glass 2. Preferably a cap 18, formed of rubber, cork or other yielding material is interposed between the flat leaf or flange 7, keeper flange 14 and seat 8 of the frame and the pane of glass 2 to prevent shock or vibration from 80 injury or breaking the pane of glass, since the keeper flange 14 will permit very slight edgewise movement of the glass under extreme conditions and absorb shock and jar.

85 Fig. 6 corresponds in most respects to the form of invention shown in Fig. 2 and illustrates the application of this form of the invention either for securing a pane of glass to a window or door frame or a panel of other material to its frame. The frame 1 is formed with a groove or channel 5 in which 90 are seated locking portions 10 and yielding spring or keeper flange 14 of the bead or retainer 6. Yielding flange 14 is engaged directly under the edge of the panel or pane 95 of glass 2 and thus absorbs such shock and vibration as may be communicated to the glass or panel and tend to cause edgewise movement thereof. The locking portion 10 is also formed with a flat face 13 and with a flat bearing member 19 seated in the bottom 100 of groove or channel 5 and which tends to retain the tension in bead or retainer 6 and prevent flatwise movement of the panel or pane of glass. In this form of the invention both the keeper flange 14 and bearing member 19 tend to resist displacement of the 105 parts.

110 In Fig. 7 the yielding flange or spring 14 is formed as a continuation of the locking portion 10 and its edge is engaged under 115 the flange or rib 9 of the frame 1 in the same manner as the keeper 14 shown in Fig. 1.

120 Fig. 8 shows a construction similar to that of Fig. 6 except that groove or channel 5 is of different shape and the keeper 14 is a continuation of the leaf or flange 7 instead of the heel 10. This keeper is turned under a fold or flange portion 9a of the metal of the frame corresponding to the rib or flange 9 of Fig. 1.

125 In some cases where it is inconvenient to form a seat or abutment for the panel on the frame, like portions 8 or 15 in Figs. 1, 2, 3 and 6, this may be included as a portion of the bead or retainer itself, and the bead 130

then also forms a groove or channel for the panel or sheet of material. Such an arrangement is shown in Fig. 9. Here the retainer is formed with the usual leaf or flange 7, and locking portion 10 seated behind the offset 12 of the frame. The spring member 14 is arched and, at its middle portion, is engaged under the edge of the panel or pane of glass 2 and at its other end bears against a shoulder or offset 21 of the frame. Continuous with the keeper 14 is a bearing member, 22, somewhat similar to the bead or retainer 6 in appearance, and having a seat or abutment 23 against which the outer side 15 of the panel 2 rests. With this form of the invention it is necessary to insert a panel into position in the frame with the beads in place on all of its edges. With a square or rectangular panel the arrangement shown 20 in Fig. 5 is convenient for easy insertion of the panel and beads into the frame and locking thereof in place. On two of the opposite sides of the frame, marked A, the offsets 12 are omitted, and the locking portions 25 10 of the beads for these sides of the frame may also be omitted if desired. On the other opposite sides, marked B, (one only being shown) the offset 12 is at full height at its middle and decreases to nothing at each 30 end. The beads are placed in position on the panel or sheet of material and are bent or distorted in the plane thereof and then slipped past the offsets 12 until the locking portions 10 seat behind the same.

35 The beads shown in Fig. 9 may be either mitered at the corners or if preferred, those marked C in Fig. 5 may be cut off square at their ends and those marked D cut away at their ends, in the manner shown at 25 in 40 Fig. 5, the cut away ends of beads D embracing and fitting the other beads C.

It will be understood that in all the embodiments of the invention shown, the bead or retainer is compressed or placed under 45 tension during the course of its insertion in the frame, and its tensed condition causes the flat leaf or flange 7 to press tightly and firmly against one face of the panel or sheet of material and force and hold the 50 same securely against its seat or abutment. At the same time, the yielding member or keeper 14 tends to resist edgewise movement of the panel and should such movement occur, causes an increase in the tension in 55 the bead and consequently greater clamping effect on the leaf or flange 7. The locking portion 10 is seated behind the offset of the frame and it is almost impossible for the bead to accidentally jump out of its depression or pocket by reason of abnormal vibration or jar of the structure. Notwithstanding 60 this, it may be easily removed by the use of a suitable tool in the manner stated. In all cases described the bead is securely seated 65 and held in place in the frame without the

usual threaded screws or bolts. In the usual constructions where a metal frame is provided, the use of screws or bolts requires the tapping of holes of comparatively small diameter in the frame and frequently cause 70 the breaking of expensive taps.

In those forms of the invention where the keeper spring 14 is seated under a fixed portion of the frame, instead of under the edge of the panel itself, as for example, in Figs. 75 1, 7 and 8, it will be understood that the keeper member does not act directly in connection with an edge of the panel to resist edgewise movement thereof, but nevertheless is yielding in nature and does so act through 80 leaf or flange 7. In this form of the invention the engagement of the keeper under the flange 9 of the frame prevents transverse rotative movement of the bead 6 around the offset 12 as an axis and thus greatly decreases 85 the liability of flatwise movement of the panel against the flange or leaf 7 and away from its seat or abutment.

It is of course obvious and will be understood that the invention is not necessarily 90 confined to railway car construction but may be also applied to general building construction or in fact wherever it is desired to removably secure a panel or sheet in 95 position.

What I claim is:

1. In a construction of the character described, the combination of a frame provided with a panel seat and a channel, a panel having portions engaging said seat, and a bead arranged to hold the panel to its seat and having one portion projecting into said channel and another free portion projecting under the edge of said panel to prevent removal of the bead from the frame, said bead 100 also having a portion resting on an exposed outer face of the frame and arranged to permit the insertion of a suitable tool between the frame and bead to remove the bead, said free portion of the bead being 105 resilient and adapted to yield under edgewise movement of the panel.

2. In a construction of the character described, the combination of a frame provided with an abutment and with an offset forming a groove therebetween, a panel having a portion engaging said abutment, and a panel retainer comprising a strip arched in cross section and having one edge provided with a flange arranged to engage said panel and hold the same to its abutment, said retainer being also formed with an indented locking member having a flat portion resting against an outer flat face of said offset and another portion projecting into said channel to thereby hold said retainer in place, said panel retainer being also provided with a resilient keeper member in said groove and projecting under the edge of said panel and arranged to prevent displacement of said 115 120 125 130

panel retainer, said keeper member being free at one edge and arranged to yield under edgewise movement of said panel.

3. In a construction of the character described, the combination of a frame having a channel and an abutment and provided with an offset spaced from said abutment, a panel having a portion resting against said abutment, and a panel retainer comprising a metal strip bent longitudinally and having a flange at one edge bearing against said panel to hold it to said abutment, and at the other edge being provided with a locking portion arranged to engage said offset, one of the edges of said strip being provided with a free keeper member located in said channel and projecting under the edge of said panel and arranged to prevent displacement of said retainer and to yield under edgewise movement of said panel.
4. In a construction of the character described, the combination of a frame having a channel and an abutment and provided with an offset spaced from said abutment, a panel having a portion resting against said abutment, and a panel retainer having one edge provided with a flange arranged to bear against said panel and hold the same to its abutment and a locking portion spaced therefrom and arranged to engage said offset, and a yielding keeper member on said panel retainer, said member being engaged

in said channel and projecting under the edge of said panel and arranged to prevent displacement of said retainer from its place, 35 said locking portion connecting said keeper member to said retainer.

5. In a construction of the character described, the combination of a frame having a channel and an abutment and provided with an offset spaced from said abutment, a panel having a portion resting against said abutment and a panel retainer having one edge provided with a flange arranged to bear against said panel and hold the same 40 to its abutment and a locking portion spaced therefrom and arranged to engage said offset, and a yielding keeper member on said panel retainer, said member being engaged in said channel and projecting under the 45 edge of said panel and arranged to prevent displacement of said retainer from its place, said locking portion connecting said keeper member to said retainer and having a flat face resting against the outer exposed face 50 of said offset to permit the insertion of a retainer removing tool or implement.

In testimony whereof, I have hereunto set my hand.

OSCAR OTTERSON.
